UNITED STATES PATENT OFFICE.

GEORGE F. WEHR, OF ROCHESTER, PENNSYLVANIA.

DESIGN FOR A SHADE OR GLOBE FOR ARTIFICIAL LIGHTS.

No. 39,294.

Specification for Design.

Patented May 5, 1908.

Application filed February 15, 1908. Serial No. 416,146. Term of patent 14 years.

To all whom it may concern:

Be it known that I, GEORGE F. WEHR, a citizen of the United States, residing at Rochester, county of Beaver, and State of Pennsylvania, have invented a new, original, and ornamental Design for Shades or Globes for Artificial Lights, of which the following is a specification, reference being had to the accompanying drawing, forming a part thereof.

Figure 1 is a side elevation of a shade for artificial lights embodying my design, and Fig. 2 is a perspective view thereof.

I claim:

The ornamental design for a shade or globe for artificial lights, as shown.

GEO. F. WEHR.
